CLOTHES CARE APPARATUS
Rhea V. Shields, East Lansing, Mich.
(1009 W. Adams, Macomb, Ill. 61455)
Filed Oct. 21, 1964, Ser. No. 405,560
3 Claims. (Cl. 223—67)

The present application is a continuation-in-part of co-pending application Serial No. 324,831.

This application is generally concerned with the drying and finishing of clothes, and more particularly relates to a device wherein a garment is subjected to a flow of conditioned air while being subjected to a constant pressure.

It is a primary object of the instant invention to provide a garment finishing device which can be easily accommodated to different size garments.

Another significant object of the instant invention is to provide a device which is easily adaptable for use in the home, or on a commercial scale in, for example, self-service laundries.

Further, an important object of the instant invention is the provision of a clothes drying and finishing device which can be utilized in conjunction with any conventional source of forced air.

Likewise, it is an object of the instant invention to provide a clothes drying and finishing device which incorporates therein means for treating, such as mothproofing, the garment or clothing as it is being finished.

In addition, it is a significant object of the instant invention to provide a device which can be collapsed for convenient storage.

Furthermore, it is an object of the instant invention to provide a device wherein a professional finish on a garment can be obtained both simply and economically.

Also, it is a significant object of the instant invention to provide a drying device which can be easily adapted for also drying various flatwork, or for that matter various objects such as carpets, mattresses, upholstered furniture, etc.

Further, it is an object of the instant invention to provide a device which is inexpensive and capable of being economically manufactured, thereby enabling even the homeowner to maintain a supply of several of the basic bag units corresponding to the various types of garments to be dried and finished.

Basically, in order to achieve the above objects, the device of the instant invention consists of an enlarged inflatable perforated bag corresponding generally in shape to a predetermined type of garment, such as for example a dress. The bag is to be preferably made of a laminate consisting of a layer of aluminum foil, for its heat conducting properties, and either one or two coating layers of a suitable plastic film for strength. The shaped bag is to include an adapter sealed within an enlarged opening in the bag and projecting therefrom for engagement with, generally by a friction fit, the discharge end of a duct leading from any conventional source of heated air. Further, in order to subject the garment being finished, which incidentally is applied over the bag, to a treating agent, the adapter includes therein a foraminous container within which the agent, such as for example mothproofing crystals, can be placed. The treating agent will of course be dispersed throughout the interior of the inflatable bag, and from there through the perforations and through the garment mounted thereon. Finally, the device includes a hanger, of any suitable non-rusting material, removably sealed within the upper end of the bag and projecting therefrom for suspension of the bag from any suitable overhead support.

These together with other objects and advantages which

2

will become subsequently apparent reside in the details of construction and operation as more fully hereinafter described and claimed, reference being had to the accompanying drawings forming a part hereof, wherein like numerals refer to like parts throughout, and in which:

FIGURE 1 is a front elevational view of the device of the instant invention;

FIGURE 2 is an enlarged cross-sectional view taken substantially on a plane passing along line 2—2 in FIGURE 1;

FIGURE 3 is an enlarged cross-sectional view taken substantially on a plane passing along line 3—3 in FIGURE 1 and illustrating a detail of the bag construction;

FIGURE 4 is an enlarged cross-sectional view taken substantially on a plane passing along line 4—4 in FIGURE 2 and illustrating the adapter including the foraminous or screen container for the treating agent;

FIGURE 5 is an enlarged cross-sectional view through the upper end of the bag illustrating the hanger and the manner in which it is mounted;

FIGURE 6 illustrates a modified form of bag adapted to accommodate a different type of garment or garments; and

FIGURE 7 is a cross-sectional view illustrating a modified form of adapter, this adapter also including the screen basket container for the treating agent.

Referring now more specifically to the drawings, the reference numeral 10 is generally used to designate the drying and finishing device of the instant invention. This device, as noted supra, consists basically of an inflatable bag 12, a hanger 14, and an adapter or duct-like connector 16.

The bag 12 itself is to be flexible and inflatable, and when inflated, assume the general configuration of a conventional garment, for example a dress as illustrated in FIGURES 1 and 2 or a pair of full length coveralls as illustrated in FIGURE 6. Incidentally, with regard to the two basic shapes illustrated, it will be appreciated that the dress form of FIGURES 1 and 2 can also be utilized as a blouse or sweater form, as well as a skirt form, while the coverall form of FIGURE 6 can be equally adapted for use as a form for shirts, sweaters, jackets and trousers. Further, when only a portion of a particular bag 12 is being utilized, the remainder of the bag 10 is collapsed and secured in its collapsed position by any suitable clip means so as to enable an increase in the flow of air through the actual part of the bag 12 being used, the significance of this being more fully appreciated in light of the following description of the operation of the device 10.

The bag 12 is to be specifically constructed of a lamination of aluminum foil and plastic film, the aluminum being desirable for its ability to quickly transfer heat, while the plastic film provides the necessary strength. Several types of pliable and flexible plastics which might be used are polyethylene film, vinylite film, polyglycol terephthalate film, etc.

As one example of the manner in which the bag 12 may be formed, the plastic film, for example polyethylene film, generally referred to by reference numeral 18 in the drawings, is extruded in molten form on aluminum foil, referred to by reference numeral 20, and subsequently cooled off. This produces a one side heat laminate, however, it will of course be appreciated that the foil 20 can be coated on both sides, if so desired, by the same process. The film thickness and foil thickness can vary according to the durability desired with probable total thickness ranging from one mil to five mils. The laminated sheet formed in this manner is then cut to the desired pattern or patterns and the seams formed by heat sealing and, if desired for added reinforcement, sewing.

After the seams are sealed together, the shaped bag is turned inside out so as to conceal the seams and prevent the forming of undesirable lines in the garments while the garments are being air dried and subjected to pressure by the inflated bag as shall be explained presently. Incidentally, in addition to sealing the seams, various types of plastic glues, for example ethylene diechloride, or solvents can be used to weld the joints.

The bag is to be provided with a plurality of airholes 22 over the entire or substantially the entire area thereof, the holes being formed in any suitable manner such as by being cold punched or heat punched. The holes 22 are of course to be relatively small and orientated so as to provide for an even flow of air therethrough and into engagement with a garment to be draped over the bag 12.

The bag 12 is, when in use, suspended from a suitable overhead support by the hanger 14, this hanger 14 being formed of plastic or other suitable non-rusting material and providing a firm formed support for the upper portion of the bag 12. The hanger 14 includes a narrow neck portion which projects upwardly through an enlarged opening 24 in the upper end of the bag 12, the edges of the bag 12 defining this opening 24 being tightly gathered about the neck of the hanger 14 and positively sealed thereto by an elastic compression ring 26, the hanging hook 28 of the hanger 14 of course projecting above the bag 12.

The connector or adapter 16 is suitably sealed within an enlarged aperture or opening 30 provided in the lower end of the bag 12 and including, if necessary, an additional integral flange of the bag material which can be tightly gathered about the connector 16 and sealed thereto by, for example, an elastic compression ring 32. The adapter 16 consists basically of an elongated tubular member 34 having an outwardly flared inner end 36 forming a flange against which the surrounding portions of the bag 12 are clamped by the external clamp 32 so as to lock the tubular adapter 16 within the garment opening or intake port 30. The outer end of the hollow tubular portion 34 is formed so as to receive the discharge end 38 of a duct 40 leading from any conventional source of forced, and preferably heated, air, and as such, will in most instances consist of a smooth cylindrical portion which can be frictionally fitted within the discharge end 38.

In addition, the adapter or connector 16 is to include a foraminous container 42, which may be in the form of a wire screen basket. This container 42 is orientated so as to project inwardly of the bag 12 from the inner end of the tubular portion 34 of the connector 16 with the open end 44 of the container being outwardly flared for engagement behind an internal annular shoulder-forming projection 46 within the inner end of the tubular portion 34. This container 42 is to be provided with suitable garment-treating material, such as mothproofing crystals or cakes 48 whereby the vapors therefrom will be carried, by the forced air, into the bag 12, and from the bag 12 through the apertures or holes 22 into the garment.

Referring now specifically to FIGURE 7, it will be noted that a modified form of adapter 50 has been illustrated therein, this adapter 50 including an elongated hollow tubular portion 52 having an annular radially outwardly projecting flange 54 on the inner end thereof, this flange 54 also projecting radially inward of the side wall of the tubular portion 52 so as to provide an annular shoulder-forming portion 56. The outer surface of the outwardly projecting portion of the annular flange 54 is stepped as at 58, with the material of the bag 12 following the stepped configuration circumferentially thereabout and being clamped and sealed thereto by an annular clamping ring 60 having a mating stepped inner face and being locked in position by a plurality of elongated bolts 62 extending therethrough and threaded into the annular flange 54. This modified form of adapter 50 also includes a

foraminous or wire basket 64 for mothproofing or otherwise treating the various garments. This container 64 also includes a laterally directed open end which engages behind the shoulder-forming annular portion 56 with this open end including a pivotally mounted cover 66 and a clip 68 for retaining it closed while at the same time allowing it to be readily opened for obtaining access to the interior of the container 64 for placing or replacing the, for example, moth crystals. The outer end of the tubular portion 52 of the adapter 50 is also adapted for engagement within any discharge end 70 of a conventional source of forced heated air, the particular discharge end 70 shown in FIGURE 7 including an expansible resilient split ring 72.

It will of course be appreciated that the number and size of the openings 22 are such so as to enable a complete inflation of the bag 12 and a maintaining of the bag 12 in its inflated condition as long as the forced air is being introduced through the adapter 16 from the conventional source of forced air being used. Further, while the use of the device as a means for drying garments will be readily apparent, it should also be appreciated that the device is equally adaptable for the finishing and removing of wrinkles from garments which have not been laundered. This is accomplished by merely introducing a predetermined amount of moisture along with the heated air, this heated moisturized air, together with the pressure exerted by the inflated bag 12, effectively removing any wrinkles which might be present. This introduction of moisture into the flow of heated air can be accomplished in any conventional manner, such as for example, utilizing the heated air being exhausted from a conventional home laundry dryer during the normal operation thereof in the drying of various other articles which would normally not need finishing. By the same token, the device can also be used to treat a garment, such as for example, mothproofing, both alone or in conjunction with a drying or finishing operation. Likewise, inasmuch as the garment-shaped bag 12 is inflatable, it will be appreciated that it can be readily collapsed and folded for compact storage, and further, can accommodate a wide range of different size garments with the inflation thereof continuing until the garment itself limits further expansion, it being contemplated that the garment, at this stage, have a constant overall pressure exerted thereon sufficient so as to remove, in conjunction with the heated air, any wrinkles which might be present. Another advantage residing in the use of a collapsible bag is the fact that various unused portions of the bag 12 can be rolled up and clipped closed so as to allow for a greater flow of air through the remaining portion of the bag. For example, when utilizing a shirt shaped garment bag to dry a short sleeved shirt, the forearm portions of the bag can be rolled up and clipped. While the above-described bags 12 have been specifically defined as assuming the shape of a garment, the instant invention also contemplates the provision of a relatively flat bag having perforations or openings in only one face thereof, such a bag being particularly useful in the drying of flatwork, carpets, mattresses, upholstered furniture, etc. Finally, the particular laminated construction of the bag itself provides for a highly durable though relatively inexpensive device with it being contemplated that each user of the device possess several bags corresponding to various garments with these bags either including their own adapter or utilizing a single interchangeable adapter.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. Clothes care apparatus comprising an enlarged vertically orientatable flexible bag, said bag being free of internal support structure and selectively inflatable and collapsible, said bag, when collapsed, being completely foldable, said bag being inflatable through the introduction of air under pressure, said introduced air constituting the sole internal means preventing said bag from collapsing, said bag, when inflated, generally conforming to the shape of and being receivable within a garment, means on said bag for selectively connecting said bag to a source of continuously flowing air for introduction of the air into said bag so as to inflate said bag, means for enabling a passage of the air from said bag over a substantial area thereof at a rate less than the rate of flow of air into the bag so as to permit a flow of air through said bag while maintaining the inflation thereof, and means for vertically suspending said apparatus from an overhead support, the means for enabling the passage of air from said bag consisting of a large number of small air passing perforations therein, said means for connecting said bag to a source of air including an enlarged opening through said bag, and a connector fixed within said opening and projecting therefrom for engagement with the discharge end of a conventional source of moving air, said connector including an internal passage therethrough so as to allow for a guided movement of the air into the bag, said means for vertically suspending said apparatus comprising a second enlarged opening in said bag, a hanger in supporting position in said bag, a hanging portion of said hanger pro-

jecting through said second opening for engagement with an overhead support, and means selectively sealing said second opening about said hanger so as to retain the hanger therein.

- 5 2. The apparatus of claim 1 including a foraminous container for a treating agent, said container being mounted within the internal air guiding passage of the connector, said container projecting inwardly of said connector into the interior of said bag.
- 10 3. The apparatus of claim 2 including abutment means projecting laterally into said internal passage adjacent the inner end of the connector, said container including a laterally directed flange portion on the outer end thereof engaged with the abutment means, thereby mounting the container on the connector with a substantial portion of the container projecting inwardly into the bag from the inner end of the connector.
